UNITED STATES PATENT OFFICE.

OWEN R. BROWN, OF CHATHAM, NEW JERSEY.

SASH-FASTENER.

1,144,635.

Specification of Letters Patent. Patented June 29, 1915.

Application filed July 31, 1914. Serial No. 854,259.

To all whom it may concern:

Be it known that I, OWEN R. BROWN, a citizen of the United States, residing at Chatham, New Jersey, have invented new and useful Improvements in Sash-Fasteners, of which the following is a specification.

This invention relates to a window sash fastener.

One of the objects of the invention is to 10 provide a device of this character by means of which the sashes of a window may be locked in open or closed position against relative movement.

Other objects are to provide a device of 15 this character which is simple in construction and therefore economical to manufacture, which is efficient, which is easily manipulated and not liable to get out of order, and which may be readily applied to any 20 existing window.

Other objects will in part be obvious and in part be pointed out hereinafter.

In the accompanying drawings showing 25 an illustrative embodiment of the invention, and in which the same reference numerals refer to similar parts of the several figures, Figure 1 is an elevational view of a window showing the device in position, the upper sash being opened; Fig. 2 is a sectional view 30 on the line 2—2 of Fig. 3; Fig. 3 is a front view of the device.

Referring to the drawings, 1 and 2 represent the upper and lower sashes, respectively, of a window of any ordinary construction. The improved sash fastener comprises a plate 3 to which a second plate 4 is hinged, as clearly shown in Fig. 2. The plate 3 is secured to the upper rail of the lower sash 2 in any suitable manner, as by 35 screws 5 passing through holes formed in the plate 3, which holes are preferably positioned centrally of said plate for a purpose hereinafter set forth.

Adjacent the free end of plate 4 is a hole 45 through which a pin 6 extends, which pin is preferably rotatable about its axis. The end of the pin 6 which projects beyond the plate 4 is adapted to engage any one of a series of recesses 7 formed in the side rail 50 of the upper sash 1. Mounted upon the other end of the pin is a locking member 8 which is adapted to rotate with the pin. The lower end of the locking member 8 is adapted to engage the upper surface of the 55 plate 3 when the locking member is in its vertical or operative position, as clearly

shown in Fig. 3, thereby preventing relative movement of the hinged plates, and when in this position the locking member will overlie the screws 5 thereby preventing them from 60 being withdrawn by any person attempting to remove the device.

If desired a plate 9 provided with holes registering with the recesses 7 may be secured to the side rail of the upper sash in 65 order to prevent the woodwork from being worn or damaged by the pin 6.

The operation of the device, which should be largely obvious from the description and illustration, is as follows:—Assuming the 70 parts to be in their operative position, as shown in full lines in Figs. 2 and 3, in which the sashes are shown closed, if it is desired to open the window it is merely necessary to move the locking member 8 sidewise into 75 the position indicated in dotted lines in Fig. 3 after which the plate 4 is rotated about the hinge into the position indicated in dotted lines in Fig. 2, thereby withdrawing the pin 6 from the recess 7 with which it 80 was in engagement. Either one or both of the sashes may then be moved into any desired position after which they may be locked against further relative movement by reversing the above described operation. 85

When the sashes are locked in the manner indicated in Fig. 1 they cannot be moved relatively to one another, although of course they may both be moved together to leave an opening at the top of the window, or at the 90 bottom of the window, or if desired they may be so moved that there is an opening at both the top and the bottom of the window.

Having described this invention in connection with an illustrative embodiment 95 thereof, to the details of which disclosure the invention is not, of course, to be limited, what is claimed as new, and what is desired to be secured by Letters Patent is set forth in the appended claims:—

1. In a sash fastener, in combination, a plate adapted to be secured to one of the sashes, a second plate hinged to said first plate, a pin carried by said second plate adapted to engage a recess in the other of 100 said sashes, and a locking member operatively connected to said pin and being adapted for engagement with the first plate to lock said second plate against movement relatively to said first plate when said pin 105 occupies its recess engaging position.
2. In a sash fastener, in combination, a

plate adapted to be secured to one of the sashes, a second plate hinged to said first plate, a rotatable pin carried by said second plate adapted to engage a recess in the other 5 of said sashes, and a locking member connected to said pin to lock said second plate against movement relatively to said first plate when said pin occupies its recess engaging position.

10 3. In a sash fastener, in combination, a plate adapted to be secured to one of the sashes, a second plate hinged to said first plate, a rotatable pin carried by said second plate adapted to engage a recess in the other

of said sashes, and a locking member connected at one end to said pin, the other end of said locking member being adapted to engage the upper surface of said first mentioned plate when said plates are at right angles to one another whereby relative movement of said plates is prevented. 15 20

In testimony whereof I have signed my name to this specification in the presence of two subscribing witnesses.

OWEN R. BROWN.
